DOILY

Edward Karfiol, Great Neck, N. Y., assignor to Royal Lace Paper Works Inc., Brooklyn, N. Y., a corporation of New York

Application December 6, 1949, Serial No. 6,434

Term of patent 14 years

(Cl. D59—2)

To all whom it may concern:

Be it known that I, Edward Karfiol, a citizen of the United States of America, residing at Great Neck, L. I., in the county of Nassau and State of New York, have invented a new, original, and ornamental Design for a Doily, of which the following is a specification, reference being had to the accompanying drawing, forming part thereof.

In the drawing the figure represents a face view of a doily, showing my new design.

I claim:

The ornamental design for a doily, as shown.

EDWARD KARFIOL.
